UNITED STATES PATENT OFFICE.

JOHN B. HUSTON, OF CLEVELAND, OHIO.

APPARATUS FOR IMPROVING THE FIRE-TEST OF PETROLEUM AND FOR BLEACHING OTHER OILS.

SPECIFICATION forming part of Letters Patent No. 297,603, dated April 29, 1884.

Application filed June 9, 1883. (No model.)

To all whom it may concern:

Be it known that I, JOHN B. HUSTON, of Cleveland, in the county of Cuyahoga and State of Ohio, have invented a new and Improved Apparatus for Improving the Fire-Test of Oil and for Bleaching Animal and Vegetable Oils, of which the following is a specification.

This apparatus consists of a cylinder or vessel having a series of chambers, one above the other, the floors of which are perforated, with the exception of the lowest one. By the side of said vessel is placed a large air-pipe having communications with the upper part of the said chambers. Within said pipe a steam-pipe and an oil-pipe are placed, the steam-pipe having connections with the lower part of said chambers, while the oil-pipe leads up to and communicates with a low chamber in the top of the aforesaid chambered vessel. The steam-pipe warms the air in the air-pipe and this warms the oil before they enter the said vessel. The branches of the steam-pipe are provided with stop-cocks. Outlet-pipes are provided to each chamber, opposite to the steam and air pipes, for the escape of the vapors. This comprises the arrangement for treatment of petroleum products. For the bleaching purpose a box for containing the bleaching material is placed near the base of the said air-pipe, to which it is connected by a short pipe. On opposite side of said box is placed an air-blower for the purpose of forcing the fumes or gases from the said box into the aforesaid chambered vessel. From the top of the said vessel a pipe leads back to said blower. This is for returning the said bleaching-gases to the blower and using them repeatedly.

The figure in the accompanying drawing is a side elevation of my improved apparatus, partly in section.

A is a cylindrical vessel, (a cylindrical form is preferable,) standing on end, and is of such dimensions as will be most convenient for working. It is divided into three or more compartments by floors *a a*, which are perforated with a large number of small perforations, the object of which will be hereinafter shown. By the side of said vessel A stands a large pipe, B, closed at the bottom, and is

connected by pipes *b b* with the several compartments near their top part. Within the said pipe B is placed a steam-pipe, C, having branch connections *c c*, provided with stop-cocks *c'*, connecting it with the several compartments in said vessel A a little above the several floors. Within said pipe B is also placed a pipe, D, passing up by the side of said pipe C, and through top of pipe B, and into the top of said vessel A, and terminating with a flaring mouth in the middle of a low chamber near the upper perforated floor. To opposite sides of said vessel A are attached pipes E, located a short distance above each floor, designed for the escape of the vapors, which may be collected and condensed, if desired. To the bottom of the vessel A is attached a pipe, F, provided with a trap for the withdrawal of the condensed steam and oil. 55 60 65 70

The operation of this is as follows; The oil to be treated passes through the pipe D from a tank located in a suitable position for the oil to run into the top chamber of vessel A, where it, spreading over the perforated floor, 75 drips through in small globules. Steam is also admitted to the chambers through the pipe C, which, coming in contact with said particles of oil, eliminates from it the vapor, which floats off through the discharge-pipes 80 E, and may be collected for condensation, if desired. The direct contact of live steam upon the particles of oil operates to more thoroughly separate the lighter elements from the oil. The several compartments in the vessel 85 A serve to divide the particles successively, so that all are affected and all the lighter vapors are fully eliminated.

Near the base of pipe B is placed a box, G, having a pipe-connection, *g*, therewith, 90 and near said box is placed a blower, H, connected by a pipe, *h'*, to the box G, at opposite end to pipe *g*, and the said blower is also connected by a pipe, I, to the top of vessel A. The purpose of the blower is to force the air 95 into the said vessel A. In the box G is to be placed a bleaching material when the apparatus is used for bleaching, and the steam is omitted and stop-cocks closed, the blast of air, forcing bleaching element into the several 100 chambers and mingling with the particles of oil, bleaches and purifies them. The oils to be

bleached are fed through the pipe D in the same manner as that for improving. The blast of air is used in both cases.

Having described my invention, I claim as follows:

The apparatus for improving the fire-test of oils and for bleaching animal and vegetable oils by a direct contact of live steam to petroleum or direct contact of bleaching material to animal or vegetable oils in a finely-divided condition, consisting of a vessel, A, divided by perforated floors *a* into two or more compartments, an air-pipe, B, connected to

the upper part of said compartments by pipes *b b*, and inclosing a steam-pipe, C, connected 15 to lower part of said compartments by pipes *c c*, and also inclosing oil-pipe D, connected to top chamber of vessel A, the vapor-escape pipes E, a box, G, for containing bleaching material, and a blower, H, connected through 20 said box to air-pipe B and pipe I with top of vessel A, substantially as described.

JOHN B. HUSTON.
